Inventor,
Henry Bailey

by H. L. Seely Attorney.

UNITED STATES PATENT OFFICE.

HENRY BAILEY, OF NEW YORK, N. Y., ASSIGNOR, BY MESNE ASSIGNMENTS
TO THE AUTOMATIC SELLING MACHINE COMPANY, OF SAME PLACE.

VENDING APPARATUS.

SPECIFICATION forming part of Letters Patent No. 402,644, dated May 7, 1889.

Application filed January 7, 1889. Serial No. 295,599. (Model.)

To all whom it may concern:

Be it known that I, HENRY BAILEY, a citizen of the United States, residing at the city of New York, in the county of New York and State of New York, have invented certain new and useful Improvements in Vending Apparatus; and I do hereby declare the following to be a full, clear, and exact description of the invention, such as will enable others skilled in the art to which it appertains to make and use the same.

My invention relates to vending apparatus of the kind in which the deposit of a coin of proper denomination unlocks the mechanism and permits a drawer or slide to be pulled out, exposing a single one of the articles of merchandise kept on sale.

It is further an improvement upon an apparatus for which I have already obtained Letters Patent, dated December 18, 1888, and numbered 394,904, which it resembles in principle, construction, and operation.

The invention consists in certain details of construction, which will be fully hereinafter described in connection with the drawings, in which—

Figure 1 is a side elevation of all the parts necessary to a correct comprehension of my invention. Fig. 2 is a central longitudinal section. Fig. 3 is a cross-section of the coin-chute. Fig. 4 is a detail of the coin-chute, and Fig. 5 is a detail of the locking-stops.

It will be understood that the apparatus shown in the drawings is set in a box or case like that shown in my application referred to, said case having a vertical holder for the packages of chewing-gum, cigarettes, or other articles, and a horizontal portion which encloses the mechanism and receives the money.

In the drawings, A is a plate which forms the top of the money-box, and is provided with flanges a—one on each side—which fit grooves in said box, as will be readily understood. This plate supports the coin-chute, which is above, and the locking mechanism, which is below, it.

The coin-chute B is mounted at the front end of the plate A, and consists of a casing, b, hinged to the plate A at b', so that it may be raised and thrown completely back for

purposes of inspection. Normally, however, it is locked down on the plate by a pin, c, which passes through a hole, c', in said plate, and two ears, b², on the casing b, which enter slots formed in plate A. The flanges a are cut away, as at a', to admit the pin, which is of course inaccessible ordinarily until the plate A is removed from the box.

The coin-chute proper is formed of two plates, b³ b⁴. In the inner face of plate b³ is formed the angular or curved passage b⁵. The plate b³ has also a long locking-stud, b⁶, which enters a hole, b⁸, in the adjacent plate b⁴, and thus prevents displacement of the two plates. Secured together thus, the two plates are fitted within the casing so that the top of passage b⁵ registers with a coin-slot in the top of the casing, while the bottom registers with a slot, d, in the plate A. Studs e e may also be formed upon the plates b³ b⁴, which bear upon the inner walls of the casing and prevent any side motion.

I shall now describe the locking and delivering mechanism, which, as before stated, is supported by and below the plate A.

D represents a sliding bar placed immediately below the plate A. At its rear end it is connected by a pin, f, to a support, E, above the plate A and sliding thereon. A long slot, e', is formed in the plate, through which the pin passes, so that the part E may be drawn forward when the bar D is pulled out. It will be understood that the support E is normally within the vertical box which contains the packages of merchandise, such packages resting on the support and being drawn out one at a time as the support is pulled forward. The bar D is guided at its rear end by its connection with the support just described and at its front end by a separate guide, g, on the plate A, and it has a coin-slot, h, normally in register with the slot d in plate a. It projects forward beyond the money-box, so that it may be readily grasped by the hand.

The sliding delivery-bar is locked by a pivoted lever, L, journaled in hangers l on plate A, and weighted at the rear, so that its forward end shall be brought close up under the coin-slot in the delivery-slide. Instead, however, of locking the bar at the forward end, 100

as in my patent above referred to, I have devised a new form of lock, which will now be described. A hanger, *k*, projects downward from the sliding bar *D*. To this is secured a plate, *k'*, carrying two stops, *k²* *k³*. The stop *k²* prevents any forward movement of the sliding bar until the front end of the locking-lever has been depressed by a coin of proper denomination falling upon it, when said bar may be drawn forward, carrying a single package or article of merchandise forward within sight and reach. The bar is retracted to normal position by a spring, *m*, connected at one end to a hanger, *n*, and at the other to a pivoted arm, *o*, both arm and hanger being connected to plate *A*. The arm *o* bears upon a pin, *q*, in the hanger *k*, and hence forces the slide *D* back when its front end has been released after being drawn forward.

The purpose of the auxiliary stop *k³* is to prevent the possibility of the slide being suddenly drawn forward and missing the stop *k²*, and both stops have forwardly-projecting lips *k⁴* and *k⁵*, Fig. 5, for additional security in this particular.

The rear end of the lever *L* may also be supported by a loop, *p*, of wire, the latter being secured to the hangers *l* and projecting backward under the lever.

Having thus described my invention, I claim—

1. In a vending apparatus, the combination, with an external coin-chute casing, of a pair of removable plates loosely held side by side within such casing and locked together, one

of such plates having a continuous recess forming a chuteway, substantially as set forth.

2. In a vending apparatus, the combination, with the hinged coin-chute casing, of a pair of removable plates loosely fitted within the same, one of such plates being recessed to form the chuteway, substantially as set forth.

3. In a vending apparatus, the combination, with a box or case containing the locking and delivery mechanism, of a hinged or pivoted coin-chute outside of said box, substantially as described.

4. In a vending apparatus, the combination, with a box or case containing the locking and delivery mechanism, of an external hinged coin-chute and a locking-pin for locking said chute to said case, substantially as set forth.

5. The combination, with the plate *A*, having the slot *e'*, of a sliding delivery-bar, as *D*, and a support for articles of sale connected to said bar by a pin which passes through said slot and sliding with said bar, substantially as described.

6. The combination of the sliding bar *D*, the locking-lever, and the double stop *k²* *k³*, substantially as set forth.

7. The combination of the sliding bar *D*, the locking-lever, and stops *k²* *k³*, each having a lip, as *k⁴* *k⁵*, substantially as described.

In testimony whereof I have affixed my signature in presence of two witnesses.

HENRY BAILEY.
